Primary Examiner — Cynthia Ramirez(74) *Attorney, Agent, or Firm* — Charles L. Thoeming(57) **CLAIM**

The ornamental design for a pallet, as shown and described.

DESCRIPTION

FIG. 1 is a top right front perspective view of a pallet showing our new design.

FIG. 2 is a front elevational view thereof.

FIG. 3 is a right-side elevational view thereof.

FIG. 4 is a top plan view thereof; and,

FIG. 5 is a bottom plan view thereof.

The pallet is shown with a symbolic break in its length and width. The appearance of any portion of the article between the break lines forms no part of the claimed design.

The broken lines in the figures show portions of the pallet, which form no part of the claimed design.
